CABLE CONDUIT WITH DETACHABLE CLOSURE PLATE

Frank R. Kinnan, Camas Valley, Oreg., assignor to
Midland-Ross Corporation

Filed Jan. 17, 1973, Ser. No. 324,499

Term of patent 14 years

Int. Cl. D13—03

U.S. Cl. D26—5 B

FIG. 1 is a perspective view of a cable conduit with detachable closure plate showing my new design;

FIG. 2 is an end elevational view thereof to a greatly enlarged scale;

FIG. 3 is a side elevational view thereof to a greatly enlarged scale and broken away in the middle for convenience of illustration; and

FIG. 4 is a bottom plan view thereof to an enlarged scale and broken away in the middle for convenience of illustration.

I claim:

The ornamental design for a cable conduit with detachable closure plate, as shown.
